REFRIGERATING APPARATUS

Donald F. Alexander and George C. Pearce, Dayton, Ohio, assignors to General Motors Corporation, Dayton, Ohio, a corporation of Delaware

Application March 31, 1936, Serial No. 71,868

10 Claims. (Cl. 62—6)

This invention relates to refrigerating apparatus.

An object of this invention is to provide a simplified form of control for air conditioning apparatus in which, at times, the power for the air conditioning apparatus is derived from a source of limited capacity.

Another object of this invention is to provide an improved control for air conditioning apparatus on a railway train, or the like, in which a source of energy of limited capacity is provided, and in which a plurality of compressing units are operated from this source, the control being such that the number of compressing units which may start simultaneously is limited, thus preventing the overloading of the source of power.

Further objects and advantages of the present invention will be apparent from the following description, reference being had to the accompanying drawings, wherein a preferred form of the present invention is clearly shown.

In the drawings:

Fig. 1 is a diagrammatic representation of a railway train to which this invention is applicable;

Fig. 2 is a diagrammatic representation of the wiring arrangement which is used to connect the various cars of the train; and

Fig. 3 is a diagrammatic representation of a slightly modified form of the invention.

This invention is applicable to a railway train, although it is to be understood that many of the features of this invention are applicable to devices or locations other than railway trains. In the railway train shown in Fig. 1, a source of power may take the form of a generator 10 driven by an internal combustion engine 11. While only one generator and internal combustion engine have been shown, it is within the purview of this invention that the source of power may include a plurality of generators and internal combustion engines. The power means may be mounted on the car 12. This car and/or other cars 13 and 14 may be provided with individual air conditioning systems which are to derive their power mainly from the generator system 10 through the leads 10a which extend throughout the train with suitable connectors between cars. If desired, as will be more fully explained, arrangements are provided so that power may be derived from the station or standby source while the train is stationary.

Any suitable type of individual air conditioning system may be used. Thus, as shown in car 13 and as may be also used on other cars, air for

the space to be conditioned is delivered by a blower 15 driven by a motor 16. This air may come from the space which is being conditioned or from the outside or both. This air is caused to flow over cooling surfaces or evaporator 17 and over heating means or coils 18 and is discharged through the grille 19 into the space 20. The refrigerating system for cooling the air during warm weather, may include, in addition to the evaporator 17, a condensing unit having a compressor 21, condenser 22, liquid receiver 23, liquid line 24 and vapor line 25. The compressor 21 is driven by a motor 26. The condenser fan 27 may be driven either from the motor 26, or, as shown, may be driven by an additional motor 28. The evaporator 17 may be of the usual finned coil variety and may include an automatic expansion valve 29 which automatically opens when the pressure in the evaporator is reduced below a predetermined limit, and the valve is also controlled by a thermostatic bulb 30 which automatically throttles the valve when the refrigerant effect extends to the outlet of the evaporator. The heating means may include a finned coil which is supplied with steam by the pipe 31 under the control of solenoid valve 32, while the condensate from the coil is discharged through the pipe 33 either through a trap to the outside of the car or is returned to the boiler as desired.

Suitable automatic control instruments are placed in a position to be affected by the condition of the air in the compartment 20. Thus, they may be placed in the compartment itself, or in an air stream which receives air from the compartment, such as the stream which returns to the blower 15. The instruments may include various air condition stats, such as a humidistat 40, a thermostat 41 which opens at a certain warm temperature, a second thermostat 42 which closes at a certain cool temperature, and a third thermostat 43 which controls the refrigerating system and which closes at a definite warm temperature. While specific thermostats and humidistats have been disclosed, it is to be understood that these may be replaced or used interchangeably, so long as they are made responsive to the desired air condition.

The generating system, which may include one or more generators 10, is provided with an automatic switch 44 which automatically closes when normal or sufficient power is being generated by the generating system. When the switch 44 closes, the automatic controls for the refrigerating system are placed in control. A source of low voltage current, such as a battery 45 is charged

from any suitable generator, and master leads from the battery 45 may extend through the train and include the negative lead 46, positive lead 47 and the power control lead 48. While a D. C. 5 battery low voltage system has been shown for operation of the controls, it is to be understood that an A. C. control current may be used, in which case 45 may be a low voltage A. C. generator. A program control 49 is placed on one of 10 the cars and so operates that only one compressor (or one group of compressors) can start at one time, as will be more fully hereinafter described. The arrangement is such that only one control wire 50 is required for the car 13, and only one 15 additional wire (51, 52, etc.) for each additional car or compressor unit is required. All of the above wires, where indicated, extend from car to car with suitable connectors between cars.

The refrigerating system control for the air 20 conditioning system is as follows. When refrigeration is required, the manual switch 53 is closed and this starts the blower motor 16 in operation. At the same time, the relay solenoid 54 is energized and this closes the relay contacts 55 and 25 56. This arrangement insures that the refrigerating system cannot be started unless the air blower 15 is started. If cooling is required, because of high temperature in the compartment 20, the thermostat 43 closes. The switch 56 is normally 30 in its upper position (when the system is not connected to standby power), and, therefore, current tends to flow from the positive battery wire 48 (if the generator control 44 permits) through the starter solenoid 57, switch 56, over- 35 load devices 58 and 59, refrigerant high pressure and low pressure control 60, thermostat 43, and contacts 55; but is arrested at the point 61 until such time as the program control 49 permits current to flow through the corresponding 40 single wire 50, contacts 62 and lead 63 to negative lead 46. The program device 49 includes a rotatable shaft 64 which progressively closes the contacts 62, 65 and 66, thus preventing the starting of more than the desired number of 45 compressors at one time. It is therefore necessary, before the compressor 21 can start, for the contacts 62 to be already co-incidentally closed, or else to have the program starting device operate until the contacts 62 are closed.

50 The program starting device 49 operates as follows. When the line or connection from lead 48, solenoid 57, switch 56, contacts 58, 59, 60, thermostat 43, contact 55, point 61 and lead 50 is completely closed, (and assuming the contacts 62 are open), current flows through the solenoid 67 and lead 63 to lead 46, thus causing solenoid 67 to close the contacts 68. This permits current to flow from the positive side 41 of the battery through the program motor 69 to the negative 64 side 46. The motor 69 drives the shaft 64 through the gear 70, thus progressively closing the contacts 62, 65, 66, etc. When the contacts 62 are closed by the rotation of shaft 64, the solenoid 67 is shunted, and if similar solenoids 71 and 65 72 are not energized, then the motor 69 is de-energized and coasts to a stop. During the time that contacts 62 are closed, current can flow through the line which includes the solenoid 57, switch 56, etc., and can now flow through the 70 lead 50 and contacts 62 to the leads 63 and 46, thus completing the circuit. When this occurs the solenoid 57 closes the contacts 73 and acts as a holding coil to maintain the operation of the refrigerating system even after the contacts 62 75 are opened and as long as the thermostat 43 re-

mains closed. When the foregoing circuit is completed, the solenoid 57 closes the motor starter contacts 74 and thus starts the motor 26 which drives the compressor 21. At the same time the condenser fan motor 28 is caused to operate. This 5 operation of the condensing unit continues as long as the thermostat 43 remains closed and as long as the overload devices 58, 59 and the high pressure and low pressure refrigerant controls 60 remain closed. When thermostat 43 opens, because 10 the car has been cooled sufficiently, or any other control opens, the refrigerating system is stopped.

It is to be seen that an undesirable number of 15 compressor motors cannot start simultaneously because the cranks 75, 76 and 77 of the program device 49 only close the contacts 62, 65 and 66 in sequence and no two such contacts are closed at the same time.

The compressor 21 may be connected to a high 20 pressure bellows 21a and a low pressure bellows 21b which are linked to the contacts 60 so that these contacts are opened whenever the discharge pressure rises above a predetermined limit or when the suction pressure falls below a predetermined limit. The contacts 58 and 59 are opened by the overload devices 58a and 59a respectively which are in series with the motors 26 and 28.

The manual switch 61a is placed between point 30 61 and the lead 46. This switch 61a is normally open, and can be manually closed whenever it is desired to shunt out the program starting device.

The refrigerating system for the car 13 (and for the other cars) may be operated from a stand- 35 by source of electricity at a station or the like. In this case the standby plug 80 is inserted in the receptacle 81 at the station, which plug is connected by the power lines 82 with the station supply of current. The plug 80 is also provided 40 with a jumper 83 which causes low voltage current to flow through the solenoid 84 when the plug 80 is placed in receptacle 81. When the solenoid 84 is thus energized the switch 56 swings to the lower contact 56', thus placing the thermo- 45 stat 43 in control of the standby current. If the thermostat 43 is closed, current can now flow through the line 85, starter solenoid 86, contacts 87 and 56', switch 56, contacts 58, 59, 60, thermo- 50 stat 43, contacts 55 to the point 61. If the stand- 55 by source of current is sufficiently powerful to start all of the refrigerating systems at the same time, the program starting device 49 may be shunted out of the control system (although it is to be understood that it be allowed to remain in control if the standby current requires sequential starting). In order to shunt the program 60 starter, contacts 88 are provided which are closed whenever suitable standby current is available. These contacts shunt the program starter by virtue of the lines 89 and 90 and may be made to close whenever the standby receptacle is plugged in. When the solenoid 86 is energized, the motor starter contacts 91 are closed and stand-by 65 current is delivered to the motors 26 and 28 under 70 the control of thermostat 43.

The box 90a is a phase rotation control of such a character that the contacts 92, 87 and 88 are closed by the flow of current through the electrical elements in the box, if the phase rotation 70 of the standby current is correct; but they are not closed if the phase rotation is incorrect. For indication purposes, a pilot light 93 is provided which lights when the phase rotation is correct. Phase rotation protectors are well known 75

and therefore this protector is not described with more particularity. A phase rotation control which may be used is more particularly described in the application of Harry F. Clark, Serial No. 708,970, filed January 30, 1934.

When it is desired to place the heating system in operation, the switch 100 is placed on the contact 101, it being understood that switch 100 is placed in an open position or in its lower position when refrigeration is desired. When switch 100 is in its upper position, current from the lead 47 can then flow through the solenoid valve 32, switch 100, thermostat 42, contacts 56 and lead 46 whenever the temperature is sufficiently low to close thermostat 42. This causes steam to flow into coil 18 and heat the car. It is, however, necessary always first to close manually the switch 53, thus energizing relay solenoid 54 and starting blower 15 before the thermostat 42 can take control of the heating system.

It may be desirable to operate the heating coil at certain times when the refrigerating system is also operating. This occurs when the temperature is fairly low and there is a large amount of humidity in the air. Under such conditions it is desirable to cool the air by evaporator 17 to dehumidify the air and then to reheat the air to avoid too low a temperature. In order to accomplish this, the switch 100 is placed on contact 102. The humidistat 40 closes when the relative humidity is high and the thermostat 41 closes only at relatively cool temperatures, being opened at high temperatures. On a cool damp day when dehumidification and reheat are required, the humidistat 40 and thermostat 41 close. This causes current to flow through the solenoid valve 32 and supplies steam to the heating coil at the same time that the refrigerating system can operate. The thermostats 41 and 43 may be so calibrated that thermostat 43 starts the refrigerating system whenever required under normal relative humidity conditions. On extremely damp and cool days, controls 40 and 41 start the heating coil, and if the temperature then rises to an uncomfortable degree, thermostat 43 starts the refrigerating system. If the temperature should rise to such an extent that the refrigerating system is likely to be taxed to or beyond its limit, the thermostat 41 opens and thus prevents the heating coil from operating even though the relative humidity is very high. It is to be understood that the humidistat 40 and thermostat 41 may, if desired, be placed outside of the car, or in the fresh air inlet to the blower 15 so as to be responsive to outside air conditions.

Under certain conditions, it may be permissible to allow the program starting mechanism to run all of the time that refrigeration is likely to be required. This may be done when the battery power is ample and is not likely to be depleted by the program control motor. Such an arrangement is shown in Fig. 3. In this modification the program start control 49a may be substituted in the wiring diagram of Fig. 2. The switch 110 may be manually closed whenever refrigeration is likely to be required. This starts the motor 69a and causes it to run continuously as long as refrigeration is likely to be required. The motor 69a drives shaft 64a through gears 70a and continuously closes the contacts 62a, 63a and 66a in sequence. Whenever a thermostat on one of the cars closes and attempts to start its corresponding compressor, such starting operation is momentarily delayed until its

corresponding contact 62a, 65a or 66a is closed. This prevents simultaneous starting of two compressors. Since motor 69a requires only a small current, it can be operated continuously without danger of depleting the battery (or of using a 5 larger amount of A. C. current).

While car 12 has been shown at one end of the train, it is to be understood that this car, or any of its contents (such as the program starter control 49 or 49a) may be placed at an intermediate position on the train. To indicate this, the wires 111, 112, 113, 114, 115 have been shown as branches which may extend to the front of car 12 in addition to, or in lieu of, those extending to the rear. Thus, lines 111, 112, 113 and 115 15 may extend to the front of car 12 in addition to those extending to the rear, while wires 114 indicate that program control wires may extend to the front of the train in addition to those extending to the rear. 20

This invention is applicable to places other than railway cars. It is applicable for the purpose of eliminating voltage fluctuations on lights, blower motors, etc., due to sudden application of heavy starting current loads. 25

The solenoids 61, 71 and 72 are made to use such a small amount of current that the current cannot energize sufficiently the solenoids 57, 86, etc. and thus prematurely start the condensing units. The time lag between closing of contacts 30 62, 65 and 66 can be varied by changing the motor speed of motor 69 by changing the relative cam positions on shaft 64 or by changing the gears at 70.

If desired, the shunting of the program starter 35 when standby current is to be used can be governed by coil 84 in lieu of, or in addition to the control at 88. This is accomplished by providing the contacts 88a which are closed upon energization of coil 84 when the plug 80 is inserted in receptacle 81. While we have referred to the current from the battery 45 as "low voltage" current, we have used this term for convenience in designation, and it is to be understood that actually this current may be equal to or even in excess of the voltage of the other currents.

The starter contact armatures of starter contacts 74 and 91 are interlocked mechanically, as by a pivoted bar, to prevent simultaneous closing of contacts 74 and 91. 50

It is understood that more than one car of the train may be equipped with air conditioning systems having controls similar to those shown on car 13. Each additional car thus equipped may be independently plugged in to standby receptacles. The cars remaining unplugged may continue to be operated from train current and remain under control of the program starter. 55

The operation is as follows:

Refrigeration systems powered from train generator system

Assuming that all refrigerating systems are idle, it is first necessary to start the blower motors 16 on each car 13, 14, etc. by closing the switch 53 65 on each car. Assuming also that two or more thermostats 43 on cars 13, 14, etc. close simultaneously, a slight current flows (in each car) through 57, 56, 58, 59, 60, 43, 55 and 61 and respectively through wires 50 and 51, solenoids 70 67 and 71 to battery 45. This closes contacts 68 and 68a, either of which starts motor 69. The cam shaft 64 turns and sequentially closes contacts 62, 65 and 66. If 62 is first closed, coil 67 is shunted out of its corresponding control cir-

cuit and a larger current can now flow through starter coil 57, closing contacts 74 and 73 of car 13. This connects motors 26 and 28 with power lines 10a and starts the condensing unit. In the meantime, crank 64 continues to rotate, because contacts 68a are kept closed by current flowing from car 14 through coil 71 and motor 69 is energized when crank shaft 64 closes contacts 65, the condensing unit motors on car 14 are started in the same manner as described with respect to car 13. As contacts 68a are opened as soon as this occurs, the motor 69 stops.

Whenever a condensing unit (or more than one condensing unit) stops, and its thermostat again attempts to start it, the program starter operates first as previously described, thus preventing the accidental simultaneous starting of two condensing units.

20 *One or more refrigeration systems powered by standby current*

When one or more plugs 80 are inserted in the standby receptacles, the corresponding condensing unit (or units) is disconnected from the train line 10a by the energization of coil 84 and consequent changing of switch 56 to contact 56'. The starter contacts are now under control of the thermostat 43 or other control devices 58, 59 and 55, as well as under control of the phase rotation control 90a.

Operation during cold weather

When cold weather is encountered, the switch 100 is placed on contact 101. If desired, a switch 100' may be placed on the refrigeration system and interlocked with switch 100 so that 100' is open when switch 100 is on 101. This causes thermostat 42 to control the steam to coil 18 by means of valve 32 and heat the car to the desired 40 temperature.

Operation in cool damp weather

When cool damp weather is encountered, the switch 100 is placed on contact 102, at which 45 time the switch 100' also closes. As the relative humidity is high and the temperature is not very high, the humidistat 40 and thermostat 41 close, turning on steam coil 18. This causes the temperature in the car to rise (if not already sufficiently high) to close thermostat 43. This causes the refrigerating system to dehumidify the air, and coil 18 to reheat the air. If the temperature rises beyond a selected limit, the thermostat 41 opens and the heating coil is turned off, permitting 55 the refrigerating system to operate alone.

While the form of embodiment of the present invention as herein disclosed constitutes a preferred form, it is to be understood that other forms might be adopted, all coming within the 60 scope of the claims which follow.

What is claimed is as follows:

1. An air conditioning system including a plurality of condensing units, a plurality of air condition stats affected by refrigeration produced by 65 said condensing units, a program control device including a plurality of sequentially closing contacts corresponding to each of said condensing units and controlling said units, a single wire extending from each of said stats to said program control device and control circuit wiring completing a sequential starting control between said stats, device and condensing units.

2. An air conditioning system including a plurality of condensing units, a plurality of air condition stats affected by refrigeration produced by

said condensing units, a program control device including a plurality of sequentially closing contacts corresponding to each of said condensing units and controlling said units, a motor actuating said contacts, a single wire extending from each of said stats to said program control device and control circuit wiring completing a sequential starting control between said stats, device and condensing units.

3. An air conditioning system including a plurality of condensing units, a plurality of air condition stats affected by refrigeration produced by 10 said condensing units, a program control device including a plurality of sequentially closing contacts corresponding to each of said condensing units and controlling said units, a motor actuating said contacts, a single wire extending from each of said stats to said program control device, means automatically starting said motor when one of said stats closes and stopping said motor 20 after the corresponding contact has closed when all other of said stats are open and control circuit wiring completing a sequential starting control between said stats, device and condensing units.

4. An air conditioning system including a plurality of condensing units, a power line of limited current capacity, starting devices between said line and said condensing units, an air condition stat for each of said condensing units, a program start device having a plurality of sequentially 25 closing contacts corresponding to each of said condensing units and controlling said units, control circuits for each of said condensing units, each circuit including a starting device, a stat, a single wire between said stat and program start 30 device and control circuit wiring completing a sequential starting control between said stats, device and condensing units, said single wire being connected to each of said stats.

5. An air conditioning system including a plurality of condensing units, a power line of limited current capacity, starting devices between said line and said condensing units, an air condition stat for each of said condensing units, a program start device having a plurality of sequentially closing contacts corresponding to each of said condensing units and controlling said units, control circuits for each of said condensing units, each circuit including a starting device, a stat, a single wire between said stat and program start device, said program start device including a motor sequentially closing said contacts, and means starting said motor when one of said stats is closed and stopping said motor after its corresponding contact has closed when all other of 45 said stats are open and control circuit wiring completing a sequential starting control between said stats, device and condensing units, said single wire being connected to each of said stats.

6. An air conditioning system including a first power line of relatively limited capacity, a second power line of relatively large capacity, a plurality of condensing units, a program control device, automatic controls for said condensing units, said program control device limiting the 50 number of units which can start simultaneously, means placing said program control device in between said condensing units and said automatic controls when connected to said first power line and for shunting said program control when 55 connected to said second power line.

7. An air conditioning system including a first power line of relatively limited capacity, a second power line of relatively large capacity, a plurality of condensing units, a program control de-

vice, automatic controls for said condensing units, said program control device limiting the number of units which can start simultaneously, means placing said program control device in between 5 said condensing units and said automatic controls when connected to said first power line, a phase rotation protector, a plug for connection to said second power line, said protector preventing connection between said plug and condensing 10 units when the phase rotation of said second power line is different from that of said condensing units.

8. An air conditioning system including a power line having generating means of relatively 15 limited capacity, control lines including a control power lead separate from said power line, means energizing said control power lead when said generating means attains a predetermined capacity, a condensing unit, starter means for connecting and disconnecting said condensing unit to said 20 power line, an automatic control for said starter means and including a control circuit between said control power lead and one of said control lines.

9. A train including a plurality of cars, generating means on one of said cars, power lines from said generating means to said other cars, a program start device on one of said cars, a single control wire for each car extending from said program start device to its corresponding car, a low voltage circuit lead extending from a low voltage source to said cars, low voltage connections to said program start device, condensing units

on some of said cars, starters connecting said condensing units and power lines, automatic controls intermittently actuating said starters, and a connection from said low voltage lead to each of said automatic starters and to the respective 5 single control wire, said program start device limiting the number of units which can start simultaneously.

10. A train including a plurality of cars, generating means on one of said cars, power lines 10 from said generating means to said other cars, a program start device on one of said cars, a single control wire for each car extending from said program start device to its corresponding car, a low voltage circuit lead extending from a low 15 voltage source to said cars, low voltage connections to said program start device, condensing units on some of said cars, starters connecting said condensing units and power lines, automatic controls intermittently actuating said starters, 20 evaporating units connected to said condensing units, blowers and blower motors for said condensing units, manual switches connecting said blower motors and power lines, relays in circuit with said blower motors, and a connection from 25 said low voltage lead to each of said automatic starters and to the respective relay and respective single wire, said program start device limiting the number of units which can start simultaneously.
